UNITED STATES PATENT OFFICE.

HARRY G. FERGUSON, OF BELFAST, IRELAND.

CARBURETER FOR INTERNAL-COMBUSTION ENGINES.

1,255,591.

Specification of Letters Patent.

Patented Feb. 5, 1918.

Application filed December 1, 1914. Serial No. 875,026.

To all whom it may concern:

Be it known that I, HARRY G. FERGUSON, a subject of the King of Great Britain, residing at Belfast, Ireland, have invented certain, 5 new and useful Improvements in and Relating to Carbureters for Internal-Combustion Engines, of which the following is a specification.

This invention relates to carbureters for 10 internal combustion engines and has for its object to provide improved methods of and means for obtaining the utmost economy at normal running or normal power periods, with the greatest possible economy combined 15 with quick readiness (when cold) of power for starting while at the same time giving a maximum of economy for slow running and ready and economical acceleration or increase of power above the normal power 20 periods when required.

With the present known forms of carbureters and carbureter controls the above noted desirable combination is impossible and to obtain maximum results in any two 25 of the above mentioned points it is necessary to sacrifice one or more of the others thereby spoiling the all around efficiency of the carbureter. For example, if any of the present known carbureters and carbureter controls 30 are set to give maximum economy then easy starting, acceleration and, what is still more serious, power when cold must be sacrificed while if set to give maximum acceleration and slow running, power when cold and 35 economy at normal running and normal power periods must be sacrificed and so on. For example an average motor car of 16 H. P. weighing 25 cwt. should average under nearly all conditions 25 miles to the gallon 40 of petrol but if one of the present day carbureters were set to give this mileage it would be at the sacrifice of some of the other things mentioned. To get the best compromise from the carbureter it is necessary 45 to set it so that the car will only do 18 miles to the gallon in order that it may give the required all around efficiency. To make any of the modern carbureters give maximum 50 results in economy, it is necessary to make a fixed alteration to the carbureter. It will be obvious that a carbureter control would be of immense value if it could be so fitted that it would be perfectly automatic in its 55 action and also adjustable from the driver's seat, thus enabling the driver to get maximum results in economy and also assisting

the carbureter in its efficiency in the other points mentioned. Such a control fitted to the above mentioned size of car would mean a saving of something like seven miles to the 60 gallon of fuel and other valuable advantages would also be gained.

A great many forms of control have been designed and fitted but to get best results from the carbureter with any of these known 65 controls it is necessary to keep altering it as the throttle is altered because they are all non-automatic in their action.

Under my invention I provide a control which while being adjustable from the 70 driver's seat is also controlled by throttle movements and adapted to admit a maximum of additional air at a predetermined range of the throttle valve or equivalent throttling movements and at greater or less 75 open positions of the throttle valve or equivalent the supply of additional air is or may be simultaneously cut off or reduced, preferably the supply of additional air is simultaneously cut off or reduced at a predetermined 80 throttle position or positions to prevent the engine stopping through weakness of mixture when running slowly and also simultaneously cut off or reduced at a predetermined throttle position or positions to 85 prevent loss of power or waste of fuel when the throttle valve or equivalent is fully opened, or in lieu of or in addition to controlling the air supply as above indicated I may by similar methods and means automatically 90 control the petrol supply in accordance with the requirements for different positions of throttle opening, admitting less petrol at a certain predetermined range of throttle valve or equivalent movements and 95 at greater or less open positions of the throttle valve or equivalent giving a proportionate or other predetermined increase in the supply of petrol in relation to the admission of air to prevent the engine stopping 100 through weakness of mixture when running slowly and also to prevent loss of power or waste of fuel when the throttle is fully opened.

In order that my invention may be clearly 105 understood I have hereunto appended explanatory sheets of drawings whereon my invention is applied to some well known type of carbureters.

Figure 1 is a view of a "Zenith" carbureter having my improved additional air control applied thereto.

Fig. 1^a is a cross section on line X—X Fig. 1.

Figs. 2 and 3, are respectively sectional side and end views of a Whyte & Poppe carbureter having my improved additional air control thereto, and

Fig. 4 is a sectional side elevation of a "S. U." carbureter fitted with my improved air control.

10 In the fitting of the control to say the "Zenith" carbureter and carbureters of its type, an air inlet pipe *a* of properly calculated dimensions for the size of carbureter it is to be used on, is fitted to the carbureter 15 *b* below the throttle valve *c*. Into this pipe *a* is fitted a piston valve comprising a piston *a*¹ or equivalent and air inlet *a*², the piston *a*¹ or equivalent being controlled from the driver's seat by means of a Bowden wire 20 *a*³ or equivalent. When the engine is cold and it is desired to get maximum power and easy and quick starting from cold the piston *a*¹ is put in a position to cover the air inlet hole *a*². When the engine warms up the 25 piston *a*¹ is pulled backward the hole *a*² uncovered and a proper mixture for economical running is thus given. If the control were fitted in this simple way it would give perfect results as regards economy, easy 30 starting, etc., but when the throttle valve would be placed in the full open position to give maximum power, the amount of air drawn through the pipe or tube *a* would be so great that the mixture would be too weak 35 and the engine would not give off its maximum power. To give maximum power it is necessary to close the air inlet *a*² from the driver's seat, and when the throttle would be brought back again it would be necessary 40 to open the control again to get economy, it will therefore be seen that the control in this form would not be automatic, and under my invention this difficulty is overcome by providing a shutter *d* which is connected 45 with and adapted to be moved by and simultaneously with throttle valve *c* and it is so made and set as shown in Fig. 1 that it will when moved as above indicated start covering the air inlet hole *a*² into the tube *a* at a 50 proper period, and when the throttle *c* is opened fully the additional air tube *a* will, by this means, be simultaneously closed or partly closed or in lieu thereof the petrol supply may be increased in any convenient 55 manner. When the throttle valve *c* is almost closed for slow running, there is of course little or no suction on the additional air inlet tube *a* so that the latter does not affect or interfere with slow running even 60 if left full open. The carbureter will then when the engine is hot, automatically give maximum results in the following:—easy starting; slow running; if fitted to a motor vehicle, steady running at low car speeds; 65 acceleration; power, whether hot or cold,

and economy. When the engine is cold it is only necessary to close the additional air inlet *a*² by moving the piston *a*¹ through the medium of the hand control to get maximum results in the above.

As an illustration of the value of the control on this carbureter I may point out that while without my control it could be fixed by a certain size of choke tube and jet to give results in economy equal to 25 miles 75 to the gallon on a certain class of car, the lack of power it would develop whether hot or cold and the difficulties of starting a cold engine would be so great that the car would be quite useless. To make the engine give 80 satisfactory results when cold and give its proper power hot or cold it would be necessary to fit jets which would reduce the petrol consumption approximately 25%; the saving in this instance therefore by adapting 85 my control is very great. In short the density of mixture required to enable the engine to be easily started and to give off satisfactory power when cold would be such that the car would only average 18 miles to 90 the gallon while a hot engine would take a sufficient amount more of air to enable the car to average 25 miles per gallon without in any way reducing its power provided the air were let in at the proper throttle positions, and under my invention as above described I provide that the air is let in just in the proper quantities and at the proper throttle positions. Similarly and under my invention the petrol supply could be controlled in accordance with throttle movements, and in certain cases this petrol control might be combined with my additional air control.

Figs. 2 and 3, show how my control may 105 be fitted to say the "Whyte & Poppe" carbureter and carbureters of its type. In this case an air inlet pipe *e* of properly calculated dimensions for the size of carbureter it is to be used on is fitted to the carbureter *f* on top of the adjusting barrel. Into this pipe is fitted a piston *g* adapted to cover and uncover an additional air inlet *h*, the piston *g* being controlled from the driver's seat through the medium of a Bowden wire *k* or equivalent. When the engine is cold and it is desired to get maximum power and easy starting from "cold" the piston *g* is put in a position to cover the air inlet hole *h*. When the engine warms up 110 the piston *g* is pulled backward, the hole *h* uncovered and a proper mixture for economical running is thus given.

In this carbureter and others of its type 115 I provide that the revolving throttle barrel *l* through which I cut a slot *l'* to let in the additional air cuts off or may cut off or reduce the air to enable me to get full power at full throttle position and also cuts off or reduces the additional air to enable me to 120

get maximum power for slow running. The additional air inlet device above described is provided at its front end with another piston m having a hole m' therethrough and it is held in contact with the top of the throttle barrel by a spring m^2 to prevent any leakage of air. The same remarks with regard to the saving of petrol and the efficiency of the carbureter in other respects apply to my 5 control on this carbureter and carbureters of its type as they are applied to the "Zenith."

Fig. 4 shows one method of applying my control to the "S. U." carbureter and carbureters of its type. In this case an additional air inlet pipe n of properly calculated dimensions for the size of the carbureter it is to be used on is fitted into the air piston cylinder o . Into this pipe n is fitted a piston n' controlling an air opening or valve n^2 the piston n' being controlled from the driver's seat by means of a Bowden wire p or equivalent. When the engine is cold and it is desired to get maximum power and easy 10 and quick starting from "cold" the piston n' is put in a position to cover the air inlet hole n^2 . When the engine warms up the piston is pulled backward, the hole n^2 is uncovered and a proper mixture for economical 15 running is thus given. To allow the air to get into the engine through my control fitting, a groove or recess r of properly calculated dimensions is cut up the air piston o' from its lower end and a groove or recess 20 s of properly calculated dimensions is cut down the wall of the cylinder o from its upper end. To prevent the engine from stopping when running slowly the groove s is cut to a properly calculated length down 25 the cylinder o and the groove r to a properly calculated length up the piston o' and when the throttle is set in the slow running position the air piston falls downward and prevents air entering through my control inlet 30 n^3 , thus the engine is automatically prevented from stopping. As in the fitting of the control to the "Zenith" carbureter, to 35 get maximum power, it is necessary that my air inlet be reduced or closed off or in lieu of this the petrol supply at such times may be increased in any convenient manner. As the throttle t is opened the air piston o' rises automatically and after it passes a certain predetermined position, automatically closes 40 off or reduces the air port n^3 of my additional air inlet valve.

The same remarks with regard to the saving of petrol and the efficiency of the carbureter in other respects apply to my control 45 on this carbureter and carbureters of its type as they are applied to it on the "Zenith."

From the foregoing the immense advantage of this control to the public will be

obvious but in addition to this it would also be of immense advantage to the manufacturers, both of carbureters and motor cars, because it is very difficult for a carbureter manufacturer to make a carbureter which will give the best compromise, and it is also impossible for a motor car manufacturer under present conditions to so adapt any carbureter to his car that it will give all around excellent results. By having a hand control in accordance with my invention, which is adjustable from the driver's seat, the car 55 manufacturer is saved an immense amount of time due to the fact that he only requires to set the carbureter to give maximum slow running, maximum power, maximum acceleration, steady running and easy starting. 60 It is the effort to obtain economy in conjunction with the other advantages which takes the time, and the fitting of my control saves this waste of time, and makes the attaining and maintaining of economy a 65 comparatively easy matter.

Having now fully described my invention what I claim and desire to secure by Letters Patent is:—

1. A carbureter having, in combination 90 with the fuel and air inlet and throttle valve therefor, a tubular member communicating at one end with the carbureter and provided with an air inlet port in the side thereof, a piston slideable within the pipe and adapted 95 to control the inlet port, a removable cover on the other end of said tubular member, elastic means interposed between said piston and said cover, means connected with said piston whereby same can be moved against 100 said elastic means, and means movable in a plane transversely to the port and independent of said piston control whereby the amount of additional air supplied to the carbureter through said inlet port is also controlled simultaneously with and by the 105 movements of the throttle valve.

2. A carbureter having, in combination 110 with the fuel and air inlet and throttle valve therefor, a tubular member forming a source of additional air supply communicating with the carbureter behind the throttle valve and having an inlet port, a valve adapted to be actuated at will to control said inlet port, and an oscillatory shutter connected with the 115 throttle valve in a plane transverse to said port and moved with said throttle valve to control the inlet port independently of said valve control.

In testimony whereof I affix my signature 120 in presence of two witnesses.

HARRY G. FERGUSON.
